UNITED STATES PATENT OFFICE.

BRADLEY DEWEY, OF CAMBRIDGE, MASSACHUSETTS, AND THEODORE T. MILLER, OF ORANGE, NEW JERSEY, ASSIGNEES TO DEWEY & ALMY CHEMICAL COMPANY, OF CAMBRIDGE, MASSACHUSETTS, A CORPORATION OF MASSACHUSETTS.

APPARATUS FOR APPLYING LINING MATERIAL TO COVERS.

Application filed February 17, 1925. Serial No. 9,826.

This invention relates to a method for controlling the distribution of a liquid on a roll, particularly upon the roll of an apparatus for applying liquid lining material to covers for cans, jars and the like and particularly to apparatus of the type shown and described in the patent to Taliaferro, No. 1,299,259, granted April 1, 1919.

In the apparatus shown and described in the said patent two rolls are employed, each rotating in the same direction at substantially the same peripheral velocity and each dipping into a bath of liquid lining material. For scraping the surface of one of the rolls to prevent an overabundant or excessive amount of the material on the second roll a knife-edge scraper is spaced a measured distance from the first roll. Thus the roll adjacent the scraper functions as a regulating roll for regulating or controlling the amount of material applied to the other roll which serves as an applying roll for applying the material to can covers which are rolled progressively along the longitudinal surface of this roll with a portion of their periphery in contact therewith, the lining material thus flowing or being scraped on to the covers.

Although the above apparatus may function in an efficient manner when using as a lining material a rubber compound dissolved in benzol, nevertheless it is not at all suitable for some other lining compounds more particularly lining compounds made with rubber latex or other emulsions.

It has been found that when lining materials of such character are used a knife-edge scraper as shown in the said patent or a scraper similar thereto revolving with the surface of the applying roll is inefficient and even a roll scraper with its surface is inadequate and inefficient because of the tendency of some of the rubber in a latex to coagulate wherever rubbing friction is encountered. As a result of such coagulation sticking to the scraper or to the regulating roll the coating on the applying roll is not smooth and of uniform thickness but is uneven and irregular so that the covers usually fail to receive a proper amount of the lining material. To maintain a uniform coating on the applying roll under such conditions it has been found necessary to clean the scraper or regulating roll at

frequent intervals, thereby consuming considerable time and labor.

Objects of this invention are to overcome the difficulties inherent in the above apparatus and to provide an efficient apparatus for distributing an even film of compound over the surface of an applying roll in the manner hereinafter described.

In accordance with this invention the applying roll dips into a bath of liquid compound but the regulating roll is preferably positioned above the bath and in close juxtaposition to the applying roll, the two rolls being suitably spaced from each other at their meeting surfaces. Both rolls may be driven in the same rotational direction, preferably the applying roll being driven at a considerably greater peripheral velocity than the regulating roll. By properly choosing the relative speeds of the two rolls and spacing them from each other an appropriate distance there may be maintained on the applying roll a coating substantially uniform throughout. No attempt is made to remove the lining material from the regulating roll and in operation this roll may be likewise coated with a small portion of the lining material stripped from the distributing roll although an overabundant amount of the material on the distributing roll is forced or directed back into the bath as will hereinafter be described.

The invention is illustrated in one of its preferred forms in the accompanying drawings, in which:

Fig. 1 is a side elevation of an apparatus for applying liquid lining material to can covers;

Fig. 2 is a section on the line 2-2 of Fig. 1;

Fig. 3 is an elevation of one end of the apparatus viewed from the right of Fig. 1;

Fig. 4 is a diagrammatic view showing the principle of the operation of the rolls; and

Fig. 5 is a view of an auxiliary feature.

The preferred embodiment of the invention illustrated comprises a flat table or support 1 supported in horizontal position above the ground by legs 2 and suitably supported upon the table 1 is an elongated rectangular pan 3 containing liquid lining material. Supported at its ends by brackets 4 and arranged to dip into the bath of the liquid lining material in the pan 3 is a rotating

applying roll 5, the lining material adhering to the roll as it dips into the bath thereby forming a coating over its entire length. Extending parallel to and having its axis 5 in substantially the same horizontal plane as that of the applying roll is a small or regulating roll 6 suitably spaced from the applying roll. For the particular purpose of applying lining material to can covers the 10 space between the two rolls is .002 and .025 of an inch depending on the character of the lining material used and the desired thickness of the coating on the applying roll. The regulating roll 6 may also be 15 rotatably supported in the brackets 4 and this roll is preferably arranged above the bath of the liquid lining material substantially as shown.

The regulating roll 6 and applying roll 20 5 are driven in the same rotational direction, but the regulating roll is driven in such a manner that its peripheral velocity is considerably less than that of the applying roll, the speed of the regulating roll preferably 25 being approximately one-third of that of the distributing roll in the illustrated embodiment in which the applying roll may be eight inches in diameter revolving at a speed of approximately fifty revolutions per minute. By this arrangement liquid is permitted to 30 flow back into tank 3 instead of being carried around with roll 6 and deposited upon roll 5 above the horizontal plane of the axis of the rolls. For this purpose a pulley 7 is fixed to one end of the distributing roll 5 and a pulley 8 considerably larger than the pulley 7 is fixed 35 to the regulating roll at the end opposite from the pulley 7. For conjointly driving the pulleys 7 and 8 a driving shaft 9 is supported in suitable brackets beneath the table 40 1 and pulleys 10 and 11 fixed to the shaft 9 are connected by belts 12 and 13 respectively to the pulleys 7 and 8. A drive pulley 14 also fixed to the shaft 9 may be connected 45 to any suitable source of power, such as an electric motor concomitantly to rotate the rolls 5 and 6 in the same direction.

The principle of operation of the rolls 5 and 6 is diagrammatically illustrated in Figure 4 in which the arrows *a* and *b* indicate the directions of rotation of the respective rolls. Assuming that the bath of liquid lining material in the pan 3 is of relatively high viscosity and plasticity, a layer or stratum A of the material adheres to the 50 surface of the applying roll 1 as it leaves the bath. Owing to the character of the lining material however a stratum B of material coheres to the stratum A of dominant adhesion, the stratum B being overbundant 55 and excessive for the required purpose. The

relatively high peripheral velocity of the applying roll plus cohesion between the strata A and B causes the stratum B to be carried with the roll until substantially the point *x* is reached when the force of gravity 70 together with cohesion between the particles of this layer B and the backflow C tend to divert a part of the stratum B into the backflow C which returns the superabundant lining material to the bath. However the surface 75 velocity and cohesion resulting from the plasticity and viscosity of the lining material are contributing factors to the carrying of a considerable amount of the material toward the nip of the rolls where the regulating roll 80 6, the surface of which is rotating in a direction opposite from the juxtaposed surface of the applying roll overcomes the cohesion, strips the overabundant material from the roll 1 and forces this into the continuous 85 web-like curtain or backflow C, the space between the rolls and relative surface velocity thereof being so chosen to maintain the backflow or curtain C continuous and coextensive with the rolls. Although the greater portion of the accumulated material from the stratum B at the nip of the rolls is returned in back flow to the bath, nevertheless a small portion thereof may adhere to the regulating roll 6 forming thereon a stratum D which 90 is carried around to the applying roll where it is added to the stratum A by cohesion, thus forming an effective coating E for applying purposes of a thickness approximately 95 equal to the stratum A plus the stratum D. 100

The covers X which are shown in the form of circular disks having upstanding peripheral flanges are rolled along the face of the applying roll 5 opposite from the regulating roll with their lower edge in contact with the roll and at a convenient angle so that as rolled progressively along the face of the roll the liquid lining material flows or is scraped on to the covers. For this purpose an endless cable 15 of rubber or other suitable material frictionally engages the covers X, passes around a sheave 16 fixed to a shaft 17 suitably supported on one end of the table 1, extends substantially parallel to the applying roll 5 over suitable guide sheaves 17' and a sheave 18 which are shown mounted on the opposite ends of the table 1. In order to maintain the cable 15 taut a weighted sheave 19 engages the cable beneath the table 1. For driving the cable 15 a sheave 20 is fixed to the shaft 17 and is connected by means of a belt 21 to a sheave fixed to the drive shaft 9, so that in this manner the applying roll 5, regulating roll 6 and endless cable or conveyor 15 are connected conjointly to be driven from a single source of power applied to the pulley 14.

As indicated in Fig. 2 the covers X are 115 120 125 130 rolled along by the conveyor 15, their lower.

edge resting upon a track 23 which extends parallel to and in close juxtaposition to the applying roll 5, and in contact with the applying roll so that as rolled along, the 5 lining material is scraped on to the covers progressively until a ring of such material is formed thereon as discharged from the opposite end of the apparatus.

It has been found that the material 10 applied to the roll 5 tends toward greater depth at the ends of the roll, probably due to surface tension, and to avoid this a scraper 24 may be associated with the distributor roll 6 in transverse alignment with 15 each end of the applying roll. These scrapers preferably incline transversely with relation to the axis of roll 6 in which case their scraping ends are curved as shown in Fig. 5. In this way the material on roll 20 6 in the region of each end of roll 5 is deflected toward the adjacent end of roll 6, thereby preventing the coating on roll 5 from acquiring excessive depth at the ends of roll 5.

25 While one embodiment of the invention has been described in more or less detail to comply with the requirements of the statute, it is nevertheless desired that this detailed description be considered merely as illustrative and not as limited, and it is to be 30 understood that changes and modifications may be made by those skilled in this art

without departing from the invention, especially as defined in the appended claims. It is also intended that this invention cover 35 the distributing of liquid or pasty compounds over the faces of applying rolls when used for other purposes, as for example in applying compounds to paper or cloth or leather, or to type or to other materials and for various purposes. 40

We claim:

1. In apparatus of the character described, a trough for holding liquid adhesive material, a rotating applying roll 45 mounted to dip in said liquid, a regulating roll parallel with, close to but spaced from, and driven in the same rotational direction as the applying roll, said regulating roll wholly above the liquid level in said trough. 50
2. In apparatus of the character described, a trough for holding liquid adhesive material, a rotating applying roll mounted to dip in said liquid, a regulating roll parallel with, close to but spaced from, and driven in the same rotational direction as the applying roll, at surface speed less than that of the applying roll, said regulating roll wholly above the liquid level in said trough. 55

Signed by us at Cambridge, Mass., this 11th day of February, 1925.

BRADLEY DEWEY.
